WILLIAM E. KAWALLE, OF OAKLAND, CALIFORNIA.

MITER-BOX.

1,092,576.

Specification of Letters Patent.

Patented Apr. 7, 1914.

Application filed October 8, 1912. Serial No. 724,616.

To all whom it may concern:

Be it known that I, WILLIAM E. KAWALLE, a citizen of the United States, residing at Oakland, in the county of Alameda and State of California, have invented new and useful Improvements in Miter-Boxes, of which the following is a specification.

This invention relates to a miter box.

It is the object of this invention to provide a miter-box that is adjustable to various positions to enable cutting at any angle, either from the inside or outside of a molding.

A further object is to provide a miter-box which is strong and durable, easily and readily assembled, and which can be quickly adjusted.

Further objects will appear hereinafter.

The invention primarily resides in providing a divided molding supporting plate, having its two sections pivoted at a common point to swing horizontally into various angles in relation to each other, forming a substantial support for the swinging molding supports, and means for quickly securing the molding supports in a rigid position at any desired angle.

The invention further consists of the parts and the construction and combination of parts as hereinafter more fully described and claimed, having reference to the accompanying drawings, in which—

Figure 1 is a plan view of the invention. Fig. 2 is a side elevation of same with parts broken away. Fig. 3 is a vertical section on the line X—X of Fig. 2, partly in elevation. Fig. 4 is a horizontal section on the line Y—Y of Fig. 3.

In the drawings A represents the base of the miter-box, which is provided with legs 2 at its corners, and is supported clear of the surface on which the miter-box is to be mounted.

The molding supporting plates are indicated at 3 and 3', which are designed to be pivotally connected at their inner ends, and mounted to swing horizontally to various angular positions in relation to each other on the base A.

The essence of this invention resides in the means for adjustably mounting the plates 3 and 3', and for locking them against movement in various positions. The mountings for the plates 3 and 3' consist of a pair of

circular toothed racks 4 and 4', a drum 5, 55 pinions 6 carried by the drum 5 engaging with the circular racks 4 and 4', and threaded pivot pins 7 and 7' pivotally connecting the toothed racks 4 and 4' and the drum 5 to the base plate A. 60

The toothed rack 4 is rigidly mounted on the inner end of the plate 3 and extends in a horizontal position, with its teeth on the underside; the rack 4 being preferably integral with the plate 3. The rack 4' is 65 formed on a hanger 8, rigidly mounted on the plate 3' and extends in a horizontal position with its teeth uppermost a short distance below the plate 3'.

The toothed rack 4' is designed to rest on 70 a bearing plate 9 formed on a hanger 10, rigidly mounted on the plate 3; the bearing plate 9 resting on the upper face of the base plate A. The drum 5 which is closed at its peripheral edge and ends, is positioned between the toothed racks 4 and 4', bearing on the latter; the pinions 6 being disposed on diametrically opposite sides on the drum 5, and meshing with the racks 4 and 4', as shown in Fig. 2. 80

The pivot pin 7 is in the form of a bolt, which extends upwardly through the base plate A, bearing plate 9, rack 4', and is threaded into the underside of the drum 5. The pivot pin 7' extends through the inner 85 end of the plate 3', passes through the toothed rack 4 on the plate 3, and is threaded into the upper side of the drum 5; the pins 7 and 7' being positioned directly opposite and in alinement with each other on the 90 axis of the drum 5, and centrally of the racks 4 and 4'. The pins 7 and 7' thus form a divided pivot around which the plates 3 and 3' may be turned in relation to each other. 95

Extending transversely through the drum 5, diametrically thereof, and supported in hubs 11 formed on opposite sides of the drum, is a horizontally extending bar 12, which bar is adapted to be rigidly secured 100 against longitudinal movement in relation to the drum 5 by means of set-screws 13 mounted in the hubs 11. Slidably mounted on the outer portions of the bar 12, adjacent its ends, are blocks 14 which are adapted to 105 be rigidly connected to the bar 12 by means of set-screws 15 carried by the blocks 14. The blocks 14 carry the usual saw-guides 16,

which are so positioned that when the saw is mounted therein, it will extend across the axial centers of the pivot pins 7 and 7', around which the plates 3 and 3' are turnable.

5 Mounted on the plates 3 and 3' are vertical alining plates 17 and 17', which plates are pivotally connected at their outer ends at 18, to standards 19 carried by the plates 10 3 and 3' adjacent their outer ends, and extend inwardly along the plates 3 and 3', and terminate at a point adjacent the pivot pin 7'.

15 The alining plates 17 and 17' are designed to be rocked in a vertical direction on the pivots 18, as indicated in dotted lines in Fig. 2; the plates 17 and 17' being rigidly secured against lateral movement when in their normal horizontal position, by means 20 of downwardly extending projections 20 formed thereon, which engage slots 21 formed in the plates 3 and 3'. This manner of mounting the plates 17 and 17' is provided as a means for enabling the workmen to raise one of the alining plates 17 or 25 17' so that a molding may be passed thereunder and rest against the other alining plate, when the plates 3 and 3' are positioned at an angle in relation to each other, 30 as indicated by the dotted lines $a-a'$ in Fig. 1.

35 Mounted on the drum 5, and surrounding the toothed racks 4 and 4' is a cylindrical casing 22, which is provided as a means for excluding sawdust from the toothed racks. The lower end of the pin 7 is formed with a round collar 23 and a square head 24; the latter being adapted to be engaged by a wrench 25 when it is desired to turn the pin 40 7 in either direction. The wrench 25 is carried by the pin 7 and is held in place thereon by means of a plate 26 secured to the pin 7; the wrench 25 being designed to be 45 lifted so that it may be freely turned around the collar 23 without turning the pin 7, then dropped into engagement with the head 24 when turned to a desired position.

50 In the operation of the invention the pin 7 is loosened sufficiently by means of the wrench 25, to permit of the plates 3 and 3' being turned freely in either direction until positioned at the desired angle in relation to each other, whereupon the pin 7 is screwed into the drum 5, thereby clamping the latter 55 against the toothed rack 4', thereby blocking the pinions 6 against rotation and thus securing the plates 3 and 3' against movement. A graduated arc 27 is formed on the upper face of the toothed rack 4 in such position 60 as to enable the workmen to set the miter-box at any desired angle. When the plates 3 and 3' have been positioned and locked against movement, a molding is placed thereon and cut in the usual manner by 65 means of the saw extending through the

saw-guides 16, which guides are adjusted to any desired position by shifting the bar 12 or the blocks 14 thereon.

It will be seen that by reason of the pinions 6 meshing with the racks 4 and 4' 70 that when either of the plates 3 or 3' is swung, the other plate will move in unison therewith in the opposite direction; the rotation of either rack 4 or 4' being transmitted to the other through the pinions 6. 75

As a means for adapting the miter-box to cutting circular or arcual pieces on a radius, a pair of removable abutment pins 28 are inserted into sockets or perforations in the upper face of the drum 5, through arcual 80 slots 29 formed in the plates 3 and 3' concentric with their pivotal points and adjacent thereto. These pins 28 are placed in position when it is desired to cut curved pieces on a radius and are removed when handling 85 straight work. In cutting this radius the piece to be cut is positioned with its peripheral surface contacting the abutment pins whereupon the plates 3 and 3' are moved and clamped in a position with the 90 alinement plates 17 and 17' contacting the edge of the circular piece. The saw will then be disposed on the radius it is desired to cut.

Having thus described my invention, 95 what I claim and desire to secure by Letters Patent, is—

1. A miter-box comprising a base, a pair of superposed continuous circular toothed racks, molding supporting plates attached to said racks, a drum interposed between said racks, pinions carried by the drum engaging with the racks, threaded pivot pins pivotally connecting the toothed racks and the drum to the base plate, and means for rotating one of said pivot pins to clamp the toothed racks and drum against movement in relation to the base. 105

2. In a miter-box, the combination of a base, a pair of superposed continuous toothed racks, molding supporting plates attached to said racks, a drum interposed between said toothed racks, pinions on said drum meshing with the toothed racks, a threaded pivot pin connecting the uppermost rack to the top of the drum, a threaded pivot pin connecting the lower toothed rack to the underside of the drum and to the base, and means for rotating said last-named pivot pin to clamp the pinions carried by the drum against the teeth of the lower rack to lock the drum and the racks against movement in relation to each other and the base. 115

3. In a miter-box, the combination of a base, a pair of superposed continuous toothed racks, molding supporting plates attached to said racks, a drum interposed between said toothed racks, pinions on said drum meshing with the toothed racks, a 125

threaded pivot pin connecting the uppermost rack to the top of the drum, a threaded pivot pin connecting the lower toothed rack to the underside of the drum and to the base, means for rotating said last-named pivot pin to clamp the pinions carried by the drum against the teeth of the lower rack to lock the drum and the rack against movement in relation to each other 10 and the base, a bar extending horizontally through the drum, means for adjustably securing the bar to the drum, and saw-guides carried by said bar.

4. A miter-box comprising a base, a pair 15 of superposed continuous circular toothed racks, molding supporting plates on said racks, a drum interposed between said racks, saw guides carried by said drum, pinions on the drum engaging the racks, and threaded pivot pins pivotally connecting the toothed racks and the drum to the base plate.

5. A miter-box comprising a base, a pair 20 of superposed continuous circular toothed racks, molding supporting plates on said racks, a drum interposed between said racks,

a horizontal bar carried by said drum, a vertical saw guide on said bar on each side of the drum, pinions on the drum engaging the racks, and threaded pivot pins pivotally connecting the toothed racks and the drum to the base plate. 30

6. A miter-box comprising a base, a pair 35 of superposed continuous circular toothed racks, horizontal molding plates on said racks, vertical molding guide plates on said supporting plates, a drum interposed between said racks, a horizontal bar adjustable on said drum, saw guides on said bar, and means for clamping the toothed racks 40 and drum to the base to hold the molding supporting plates and saw guides against horizontal movement in relation to each other.

In testimony whereof I have hereunto set 45 my hand in the presence of two subscribing witnesses.

WILLIAM E. KAWALLE.
